ORE PULVERIZER

Joseph C. Thurman, St. Louis, Mo.

Application June 17, 1938, Serial No. 214,212

4 Claims. (Cl. 83—12)

The present invention relates generally to pulverizing machinery, and more particularly to gravity pulverizers for freeing ore from a carrying body.

5 An object of the present invention is to provide an ore pulverizer which is adapted to free ore from a carrying body by a series of crushing operations.

10 Another object is to provide an ore pulverizer which is adapted to remove ore from a carrying body and to leave the free ore in fragments of flattened slightly convexed configurations.

15 Another object is to provide an ore pulverizer which includes a plurality of superposed pairs of frusto-conical rollers adapted to crush ore from a carrying body and to leave the free ore in flattened, slightly convexed fragments.

20 Another object is to provide an ore pulverizer of sectional construction whereby a large unit can be reduced to two or more smaller units.

25 Another object is to provide an ore pulverizer comprising a plurality of superposed pairs of frusto-conical rollers, one vertical series of which is spring-pressed into engagement with the other vertical series.

30 Another object is to provide an ore pulverizer which is sturdy in construction, readily and easily assembled or dismantled, and thoroughly efficient in operation.

35 Another object is to provide an ore pulverizer which includes a plurality of superposed pairs of frusto-conical rollers, adjacent pairs of which are oppositely disposed to provide a gravity track from the uppermost pair of rollers to the lowermost pair of rollers for the material being crushed.

40 Another object is to provide an ore pulverizer which includes a plurality of superposed pairs of frusto-conical rollers, the uppermost pair of which is corrugated and the remaining pairs of which are smooth.

45 Another object is to provide an ore pulverizer having a frame of opposed sections yieldingly pressed into cooperative disposition.

50 Other objects and advantages will be apparent from the following description, taken in conjunction with the accompanying drawings, in which:

Fig. 1 is an end elevation of an ore pulverizer constructed in accordance with the teachings of the present invention, parts being broken away for clarity;

Fig. 2 is an end elevation of the ore pulverizer shown in Fig. 1 turned through 180°, parts being broken away for clarity;

55 Fig. 3 is a side elevation of the ore pulverizer shown in Fig. 1;

Fig. 4 is a section on the line 4—4 of Fig. 1;

Fig. 5 is a section on the line 5—5 of Fig. 4;

Fig. 6 is a section on the line 6—6 of Fig. 3;

60 Fig. 7 is a section on the line 7—7 of Fig. 3;

Fig. 8 is a section on the line 8—8 of Fig. 6; and

Fig. 9 is a section on the line 9—9 of Fig. 3. Referring to the drawings more particularly by reference numerals, 10 indicates generally an ore pulverizer constructed as a preferred embodiment of the present invention. The pulverizer 10 includes a lower section 11, an upper section 12, and a feed mechanism 13.

The lower section 11 comprises two opposed halves 15 and 16. The section half 15 includes a frame 17 (Fig. 7) comprising an end plate 18 and side plates 19 and 20. If preferred, top and bottom bracing members can replace the end plate 18 to tie the side plates 19 and 20 together. Angle strips 21 and 22 connect the side plates 19 and 20, respectively, to the end plate 18. The angle strips 21 and 22 are of acute cross-section and are fixed to the side plates 19 and 20 by welding, or other means, and to the end plate 18 by rivets 23, or the like.

The side plate 19 has a large cut-away 25 (Fig. 1) in one vertical edge and two spaced apertures 26, the top one of which is shown in Fig. 7. A lug 27 having a threaded aperture therethrough is fixed to the plate 19 adjacent the cut-away 25 and adjacent each of the apertures 26. Apertured lugs 28 are fixed to the plate 19 adjacent the vertical edge having the cut-away 25. A pair of identical members 30 is fixed to a lower corner of the plate 19, one to each side, and extends angularly therefrom for a purpose to be described. A member 31 of the configuration of the members 30 is fixed to the plate 19 at an upper corner on the inwardly disposed side.

The plate 20 has two large vertically disposed cut-aways 25 (Fig. 2) in one edge, and an aperture 26 substantially centrally thereof. A lug 27 having a threaded aperture therethrough is fixed to the plate 20 adjacent each of the cut-aways 25 and adjacent the aperture 26. Apertured lugs 28 are fixed to the plate 20 adjacent the vertical edge having the cut-aways 25. A pair of identical members 30 is fixed to a lower corner of the plate 20, one to each side, and extends angularly therefrom for a purpose to be described. A member 31 of a configuration similar to the members 30 is fixed to the plate 20 at an upper corner on the inwardly disposed side.

The end plate 18 is cut away at each of the four corners to provide room for the members 30 and 31.

A supporting leg 35 of a configuration shown in Figs. 1 and 3 is disposed between each pair of members 30, being maintained in position by an elongated bolt 36 and nut 37.

The section half 15 supports three vertically superposed frusto-conical rollers 39, 40, and 41 in the identical relationship of frusto-conical rollers 39', 40', and 41' supported by the section 60

half 16 (Fig. 3). The rollers 39 and 41 have the small end adjacent the plate 20, whereas the roller 40 has the small end adjacent the plate 19. Each of the rollers 39, 40, and 41 is fixed to a shaft 42 which is journaled adjacent each end of the respective roller in bearings 44 and 45 (Figs. 6 and 7).

Each of the bearings 44 is supported by a cover plate 46 adjustably fixed to one of the side plates 19 or 20 over a cut-away 25, each plate 46 being of a configuration shown in Figs. 1 and 7 to permit the small end of the roller to extend through the associated cut-away 25. Each plate 46 is connected to the respective side plate 19 or 20 by bolts 47 which extend through slots 48 in the plate 46 and through apertures in the respective side plate 19 or 20. A lug 49 is fixed to each plate 46 in opposed relation to the associated lug 27 which is adapted to be contacted by one end of a threaded member 50 threadedly engaging the lug 27.

Each of the bearings 45 is supported by a plate 54 adjustably fixed to one of the side plates 19 or 20 over an aperture 26, each plate 54 being shown of square configuration. Each plate 54 includes slots 56, and a lug 55 adjacent one edge disposed in cooperative relation to the associated lug 27. Bolts 57 extend through the slots 56 and through apertures in the respective side plate 19 or 20 to maintain the plate 54 in adjustable relation with the respective supporting side plate 19 or 20. The lug 55 abuts the threaded member 50 threadedly engaging the lug 27.

The section half 16 is identical with the section half 15, with the exception that the various elements thereof are disposed in opposed relation and, therefore, detailed description thereof is unnecessary.

The section halves 15 and 16 are disposed in abutting relation with the side plates 19 and 20 in engagement, as is clearly shown in Figs. 1, 6, and 7. A bolt 60 extends through each opposed pair of lugs 28. A heavy helical spring 61 is disposed about the bolt 60 with one end resting against one of the lugs 28 and the other end against a washer 62 which is maintained in a predetermined position by a pair of lock nuts 63. This heavy resilient connection permits limited separation of the section halves 15 and 16 during operation of the pulverizer 10.

The upper section 12 comprises two opposed halves 65 and 66. The section halves 65 and 66 are identical with the section halves 15 and 16, respectively, with the exception that in each of the section halves 65 and 66 the members 31 are omitted, the lugs 28 are spaced further apart than the lugs 28 of the halves 15 and 16, and the upper roller 69' or 69, respectively, is longitudinally corrugated or fluted and is supported by cover plates 46' (Fig. 1) and 54' (Fig. 2) which are of slightly larger dimensions than the cover plates 46 and 54, necessitated by the increased diameter of the rollers 69 and 69' occasioned by the corrugations thereof. The section half 65 supports beneath the roller 69' rollers 68' and 67' and the section half 66 supports beneath the rollers 69 rollers 68 and 67. It is, therefore, unnecessary to further describe in detail the elements of the section halves 65 and 66, the elements thereof corresponding to the elements of the section halves 15 and 16 being given the same reference numerals as are applied to the section halves 15 and 16.

The upper section 12 is operatively superposed on the lower section 11 and is maintained there-

on by bolts 70 extending through apertures in the members 31 of the section halves 15 and 16 and through apertures in the members 30 of the section halves 65 and 66, the bolts 70 being secured by nuts 71. The members 31 extend 5 between the members 30 (Fig. 3).

The shaft 42 of the roller 69' is extended beyond both bearings 44 and 45 and receives fixed thereto adjacent the bearing 44 a pulley 73 and adjacent the bearing 45 a pulley 74. The shaft 10 42 of the roller 68' extends beyond the bearing 45 and has fixed thereto a pulley 75. The shaft 42 of the roller 67' extends beyond the bearing 45 and has fixed thereto two pulleys 76 and 77. The shaft 42 of the roller 41' extends beyond 15 the bearing 45 and has fixed thereto two pulleys 78 and 79. The shaft 42 of the roller 40' extends beyond the bearing 45 and has fixed thereto a pulley 80. The shaft 42 of the roller 39' extends beyond the bearing 45 and has fixed 20 thereto three pulleys 81, 82, and 83.

A continuous flexible belt 84 connects the pulley 83 to some source of power, such as the driven shaft of a motor (not shown). A continuous flexible belt 85 connects the pulleys 73 25 and 82; a continuous flexible belt 86 connects the pulleys 79 and 81; a continuous flexible belt 87 connects the pulleys 75 and 78; a continuous flexible belt 88 connects the pulleys 74 and 76; and a continuous flexible belt 89 connects the 30 pulleys 77 and 80.

The rollers of the right vertical series (Fig. 1) are also positively driven, power therefor being taken from a pulley (not shown) fixed to the end of the shaft 42 of the roller 68 adjacent the 35 bearing 44.

The feed mechanism 13 is mounted on a top plate 95 fixed to the upper section 12 and forming a cover therefor. A pair of spaced angle members 96 is fixed to the end plate 18 by rivets 40 97, or the like, and are braced in spaced relation by an angle member 98. An angle member 99 (Figs. 3 and 9) is fixed to each angle member 96 at the free end thereof and right angularly thereto. A narrow plate member 100 is fixed to 45 each of the angle members 99 towards the free end thereof in a position to parallel the angle members 96. The lower end of each of the plate members 100 is fixed to an angle member 101 which, in turn, is fixed to the top plate 95. 50

A feed chute 102 is disposed between and partially supported by the plate members 100. The chute 102 includes end plates 103, one being attached by rivets 104, or the like, to each of the plate members 100, and side plates 105 of the 55 cross-section shown in Fig. 1 to provide a sloping portion and neck portion of the chute 102. The side plates 105 are fixed to angle members 106 which are, in turn, fixed to the top plate 95. Each of the side plates 105 has a slot 107 60 which extends transversely thereacross. A movable gate plate 108 is disposed against the outer surface of the sloping portion of each of the side plates 105 and extends adjustably through the slot 107. A lever 110 (Fig. 3) is 65 pivoted to each of the gate plates 108 at 111 and is, in turn, fulcrumed at 112 (Fig. 4) on a bracket 113 fixed to the respective end plate 103. Each lever 110 has a slot 114 (Fig. 3) therethrough to prevent binding of the gate plate 108 in its 70 movement. Brackets 115 maintain each gate plate 108 in sliding relation to the respective side plate 105. Brace plates 116 fixed to the plate members 100 and the end plates 103 give added rigidity to the chute 102. A square frame 75

117 supported by and between the plate members 100 constructed of angle members is adapted to support a screen to be used for the purpose of screening the material passed into the pulverizer.

5 The belts and pulleys for positively driving the rollers 39, 40, 41, 67, 68, and 69 have been omitted for the purpose of clarity, the affected shafts 42 being shown broken off in Figs. 1 and 2. However, it is to be understood that the twelve rollers 10 are positively driven, although in the crushing of certain materials it may be found advisable to drive only one vertical set of six rollers, in which case the belts can be readily removed from the other six rollers, which will result in 15 an idler rotation of the said second set of rollers. Any relationship of the driving belts may be employed. Chains and sprockets, or other driving means, may be used.

The elements of the pulverizer 10 are constructed of material suitable to withstand the heavy usage to which the machine is necessarily put. The slope of the frusto-conical rollers may be varied to increase or decrease the gravity action. When set up for operation, a cover is 25 disposed about the pulverizer 10 in order both to protect the machine and to prevent injury to an operator, or other person.

Operation

30 The assembly of the pulverizer 10 is apparent from the foregoing detailed description. After the initial adjustments have been made to the pulverizer 10, material is introduced to the top pair of rollers 69 and 69' through the chute 102. 35 When necessary, the material to be crushed is passed through a screen disposed in the frame 117. The flow of material into the pulverizer 10 is regulated by the gate plates 108.

As the rollers are power rotated, the material 40 fed through the chute 102 is drawn between them in succession until it passes into some suitable receiving container or conveyor (not shown). An inspection of Fig. 3 clearly shows the gravity track provided by the disposition of the frusto-conical rollers. The arrows A indicate the zig-zag path of material passing through the rollers. The gravity movement of the material along succeeding paths of rollers effects a number of advantages which cannot be achieved by cylindrical rollers. The material is prevented from piling at any one point between a pair of rollers, since the gravity path tends to move the material along the pair of rollers to insure that the crushing operation be done by the full surfaces 50 thereof. Further, the resultant diagonal or spiral passage of material between the frusto-conical rollers produces flattened fragments of convex configuration which is desirable in that it assists in the carrying on of subsequent treatments. The use of the longitudinally corrugated or fluted rollers 69 and 69' to initially receive material to be crushed affords a positive reception for the material in its larger proportions. The present pulverizer does not grind in the 65 sense of prior machines, but crushes the ore from the carrying medium by a direct application of spirally applied pressure.

The resiliently joined section halves 15, 16 and 65, 66 prevent breakage of the working parts 70 of the pulverizer 10, inasmuch as the sections give outwardly a predetermined amount when non-rushable objects are placed between a pair of rollers. The adjustable cover plates 46, 46',

54, and 54' permit continued use of rollers after wear, and permit selected spacing of the rollers of a pair to receive for crushing fragments of varying sizes.

Experience has proved that six pairs of rollers 5 is the ideal number for effectively crushing a variety of ore-bearing materials to remove the ore therefrom. However, the pulverizer 10 is constructed sectionally so that in any operations not requiring such thoroughness of crushing as 10 is contemplated for the complete machine, the upper section 12 can be removed from the lower section 11, legs attached thereto, and a feed mechanism attached to the lower section 11 to provide two pulverizers of three pairs of rollers 15 each.

It is to be understood that the foregoing description and accompanying drawings have been given by way of illustration and example and not for purposes of limitation, the invention being 20 limited only by the claims which follow.

What is claimed is:

1. An ore pulverizer comprising a plurality of pairs of superposed frusto-conical rollers, the rollers of each pair having the small ends and the 25 large ends, respectively, in adjacent relationship, the small ends of any one pair of rollers being disposed over the large ends of the pair of rollers directly beneath and the large ends of said any one pair of rollers being disposed over the small 30 ends of the said pair of rollers directly beneath, and means supporting said rollers.

2. An ore pulverizer comprising a plurality of pairs of superposed frusto-conical rollers, the uppermost pair of rollers being longitudinally 35 corrugated and the remaining pairs of rollers being smooth, the rollers of each pair having the small ends and the large ends, respectively, in adjacent relationship, the small ends of any one pair of rollers being disposed over the large ends 40 of the pair of rollers directly beneath and the large ends of said any one pair of rollers being disposed over the small ends of the said pair of rollers directly beneath, and means supporting 45 said rollers.

3. An ore pulverizer comprising a frame, a plurality of pairs of superposed frusto-conical rollers supported within the frame, the rollers of each pair having the small ends and the large 50 ends, respectively, in adjacent relationship, the small ends of any one pair of rollers being disposed over the large ends of the pair of rollers directly beneath and the large ends of said any one pair of rollers being disposed over the small 55 ends of the said pair of rollers directly beneath, and an adjustable feed mechanism supported on the frame.

4. An ore pulverizer comprising a frame, a plurality of superposed pairs of frusto-conical rollers supported by said frame, the axes of the rollers of each pair of rollers lying in a horizontal plane, and means for rotating said rollers of each pair towards each other, the rollers of each pair of 60 said rollers being disposed with the small ends and the large ends, respectively, in adjacent 65 relationship to provide a segmental sloping path for material being crushed, said segmental sloping path of each pair of rollers being determined by the decrease in radius of the rollers from the large ends to the small ends, whereby ore is 70 crushed into flattened convex fragments.

JOSEPH C. THURMAN.
